[57] CLAIM

The ornamental design for a table, as shown.

DESCRIPTION

FIG. 1 is a prospective view of the table of applicant's invention;

FIG. 2 is an elevational end view of FIG. 1;

FIG. 3 is an enlarged fragmentary view partly in section of a part of the support members of applicant's invention; and

FIG. 4 is an enlarged cross-sectional view taken along the line 4—4 of FIG. 3 showing the manner in which the glass table top is supported by the framework.

FIG. 1.

FIG. 2.

FIG. 3.

FIG. 4.
